Primary Examiner — Kevin Rudzinski(74) *Attorney, Agent, or Firm* — Hamre, Schumann, Mueller & Larson, P.C.(57) **CLAIM**

The ornamental design for a rotary apparatus for solar light, as shown and described.

DESCRIPTION

FIG. 1 is a perspective view of the rotary apparatus showing my new design; and

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof, shown in a position of use.

The broken lines shown in FIG. 8 illustrating environmental structures form no part of the claimed design.
